Inventor

Charles Lucas

By his Attorney

Franklin W. Donnell

UNITED STATES PATENT OFFICE.

CHARLES DUCAS, OF NEW YORK, N. Y., ASSIGNOR, BY MESNE ASSIGNMENTS, TO LUKENS STEEL COMPANY, A CORPORATION OF PENNSYLVANIA.

SECTIONAL-FIRE-BOX CONSTRUCTION.

1,322,484.

Specification of Letters Patent. Patented Nov. 18, 1919.

Application filed July 24, 1916. Serial No. 110,913.

To all whom it may concern:

Be it known that I, CHARLES DUCAS, of New York, in the county of New York, and in the State of New York, have invented a 5 certain new and useful Improvement in Sectional-Fire-Box Construction, and do hereby declare that the following is a full, clear, and exact description thereof.

My invention relates particularly to sectional fire-boxes designed for use in locomotives, although it is applicable also to sectional fire-boxes used for other purposes.

The object of my invention is to provide a sectional fire-box construction in which 15 the sections of the fire-boxes are connected with the wagon top in such a manner as to permit relative movement of the same so as to avoid damage due to differences in expansion and contraction in the various parts. 20 More particularly the object of my invention is to provide a construction of this character in which the fire-box sections may move vertically and horizontally in a transverse direction, as well as longitudinally of 25 the fire-box with regard to the wagon top, without producing damage to the parts due to differences in expansion and contraction. A further object of my invention is to provide for rocking movement between the fire- 30 box sections and the wagon top so as to avoid such damage.

While my invention is capable of embodiment in many different forms, for the purposes of illustration I have shown only certain forms thereof in the accompanying drawings, in which—

Figure 1 is a vertical section of a portion of the fire-box made in accordance with my invention; Fig. 2 is a horizontal section 40 through the same; Fig. 3 is a vertical section of a modified form of fire-box made in accordance with my invention; and Fig. 4 is a horizontal section through the same.

In the drawings, reference being had to 45 Figs. 1 and 2, I have shown a mud ring 1 having attached to the outside thereof a plurality of wagon top sections 2, between the edges of which there are located stay sheets 3, preferably in the form of flexible or 50 yieldable plates, rivets 4 being provided for connecting the edges of the sections 2 and the stay sheets 3 together. To the inner surface of the mud ring 1 there are connected a plurality of fire-box sections 5 between the edges of which there are located 55

strips 6, rivets 7 being provided for connecting the strips 6 with the fire-box sections 5. The strips 6 are widened at the top of the fire-box to provide extensions 8 which are connected by a plurality of bars 9 to the upper portions of the stay sheets 3. At the sides of the fire-box sections 5 the edges thereof are extended beyond the rivets 7 to form flanges 10 having holes 11 to receive pins 12 which are fixedly secured to the stay sheets 3. The holes 11 are larger in diameter than the pins 12, the pins being located as shown in Figs. 1 and 2 adjacent to the outer sides of said holes 11.

The modification of my invention shown 70 in Figs. 3 and 4 is constructed the same as the modification previously described except that instead of stay sheets 3 there are folded stay sheets 13 located between the wagon top sections 2 said folded stay sheets 75 13 having their folded edges provided with holes 14 to receive rods 15 and being provided with rectangular recesses 16 along said folded edges; and except that instead of the strips 6 and the flanges 10 there are 80 provided inner folded stay sheets 17 having holes 18 at their folded edges to receive the rods 15 and rectangular recesses 19 alternating with recesses 16, the inner folded stay sheets 17 being themselves connected to 85 the bars 9.

In the operation of the form of my invention shown in Figs. 1 and 2, in the use of the fire-box any differences in expansion and contraction in the fire-box sections 5 90 relative to the wagon top sections 2 will not result in any damage to the parts, since the sections 2 and 5 may move with regard to one another to a certain extent both vertically and horizontally in a transverse plane, 95 owing to the loose connection between the pin 12 and the flanges 10. Relative longitudinal movement between said sections also is permitted by flexing of the stay sheet 3, since such stay sheet may be made more or less flexible, and the difference in size between pin 12 and holes 11 will permit said pin to rock therein so as not to resist such longitudinal movement. At the same time the sections 5 and 2 are adequately supported from one another as the greatest pressure is the pressure tending to separate sections 5 and sections 2 due to the pressure of the steam between said sections, while at the same time the pins 12 are located in the 110

holes 11 in such a position as to prevent any movement of separation by the sections 5 and 2.

The form of my invention shown in Figs. 5 3 and 4 operates in the same manner as the modification already described so far as the kind of movements is concerned except that not so great a degree of movement is permitted horizontally in the plane of each 10 of the fire-box sections 5, while at the same time a greater degree of rocking and pivotal movement is permitted on each vertical axis.

While I have described my invention 15 above in detail I wish it to be understood that many changes may be made therein without departing from the spirit of my invention.

I claim—

- 20 1. In combination, a firebox section, an outer section spaced therefrom, a flexible stay sheet extending between said sections, said sheet being fixedly connected to a side of one of said sections, and having a loose connection with the adjacent side of the remaining section.
- 25 2. In combination, a pair of U-shaped firebox sections, a pair of U-shaped outer sections spaced therefrom, a stay sheet secured between adjacent sides of one of said pairs of sections, and means loosely securing said stay sheet between adjacent sides of the remaining pair of sections.

3. In combination, a pair of U-shaped firebox sections, a pair of U-shaped outer sections spaced therefrom, a stay sheet secured between adjacent sides of one of said pairs of sections, and a pin and slot connection between said stay sheet and adjacent sides of the remaining pair of sections. 35

4. In combination, a pair of U-shaped firebox sections, a pair of U-shaped outer sections spaced therefrom, a flexible stay sheet secured between adjacent sides of one of said pairs of sections, and means loosely 45 securing said stay sheet between adjacent sides of the remaining pair of sections.

5. In combination, a pair of U-shaped firebox sections, a pair of U-shaped outer sections, a flexible stay sheet secured between adjacent sides of one of said pairs of sections, and a pin and slot connection between said stay sheet and adjacent sides of the remaining pair of sections. 50

6. In combination, a pair of U-shaped firebox sections, a pair of U-shaped outer sections inclosing the same, a stay sheet secured between adjacent sides of one of said pairs of sections, a spacing strip secured between adjacent sides of the remaining pair 60 of sections, and means loosely securing said stay sheet between said last mentioned sides in line with said spacing strip.

In testimony that I claim the foregoing I have hereunto set my hand.

CHARLES DUCAS.
